Attorney.

UNITED STATES PATENT OFFICE.

ALICE F. LEACH, OF BROOKLINE, MASSACHUSETTS.

TENT.

Application filed June 20, 1925. Serial No. 38,524.

My invention relates to collapsible tents.

With the advent of automobile camping trips a tremendous demand has arisen for a collapsible tent that can be folded into a very small space and which weighs very little. The chief object of my invention is to provide a tent especially adapted for this use constructed of very few parts, cheap, yet rugged and convenient.

10 I am aware that tent frames having ribs which open and close similar to umbrella ribs have been provided and one feature of my invention relates to improvement in this type of frame. My improved tent frame 15 comprises a centre pole having its top preferably radially enlarged, ribs having inclined inner ends, hinges joining the inclined inner ends of said ribs to the sides of the enlarged pole top, a runner element having a flat upper side slidable on said pole, brace arms having flat lower ends and inclined upper ends, hinges joining the inclined upper ends of said brace arms to the underside of said ribs, hinges joining the 20 flat lower ends of said brace arms to the flat upper sides of said runner and means to support said runner, brace arms and ribs in raised position on said pole. I am aware that the brace arms have been pivotally joined to the runner element, the ribs pivotally joined to the runner element, the ribs pivotally joined to the pole and the brace arms pivotally joined to said ribs, but so far as I am aware no one has used hinges for 25 this purpose. By providing hinges I accomplish the following new results. When the frame has been raised to open position the inclined inner ends of the ribs abut the enlarged pole top to limit the outward movement of the frame and the inclined upper ends of said brace arms rest flatly against the lower sides of said inclined ribs thereby more strongly supporting the ribs than has been done hitherto. When the frame is 30 lowered to closed position the flat lower ends of said brace arms abut the flat upper surface of the runner thereby retaining the entire frame in very compact position.

So far as I am aware it is new to place 35 the guy ropes of a tent at an angle to the tent pole underneath the tent canopy where by they may support the walls of the tent. Hitherto the guy ropes have been attached to the corners of the tent outside of the canopy where they put great strain on the corners and portions of the tent to which they

are attached, all of which strain comes on one spot. By attaching the guy ropes to the frame and to tent pegs spaced at a greater radial distance from the pole than the portion of the frame to which they are attached, I eliminate all this strain on the tent and permit the guy ropes to support the walls thereof.

These and such other objects of my invention as may hereinafter appear will be best understood from a description of one embodiment thereof such as is shown in the accompanying drawings.

In the drawings, Fig. 1 is a perspective view of my improved tent.

Fig. 2 is a perspective view of the frame and guy ropes thereof in open position mounted on the ground.

Fig. 3 is a perspective view of a tent frame in closed position for travel.

In the drawings, wherein like characters of reference indicate like parts throughout, 10 generally indicates the tent pole which may comprise the detachable sections 10^a, 10^b and 10^c which may be joined together as indicated as 12 similar to the manner of joining fish pole sections. The top of the tent pole is preferably radially enlarged as shown at 14. I provide the ribs 16 adapted to project radially at an angle from the top of the tent in similar fashion to umbrella ribs. I preferably incline the inner ends of said ribs as shown at 18 and mount the eyes 20 on the outer ends thereof. In my preferred embodiment I have shown four ribs 16. As stated I preferably join the ribs to the enlarged pole top 14 by means of the hinges 22, one side 24 of said hinges being attached to the enlarged pole top 14 and the other side 26 of said hinges being preferably screwed to the underside of said ribs 16 adjacent to the inclined inner ends 18 thereof. I provide the runner element 28 slidable on the pole 10. In my preferred embodiment the runner comprises the flat disc 28 having the central opening 30 therein for insertion over said pole. I provide the brace arms 32 which preferably extend from said runner element 28 up to said ribs 16 to support them when in raised position. I preferably provide said brace arms with the flat lower ends 34 for a purpose to be described and the inclined upper ends 36. I provide hinges 38 to join the inclined upper ends 36 of said brace arms 32 to the underside of said ribs 16, one portion 40 of said

hinges being screwed to the under side of said ribs 16 and the other portion 42 being screwed to the sides of the brace arms adjacent to their inclined upper ends 36. I 5 provide the hinges 44 to secure the flat lower ends of said brace arms 32 to the upper side of said disc 28, one portion 46 of said hinges being secured to the periphery of said disc 28 and the other portion 48 of said 10 hinges being secured to the sides of said brace arms adjacent to their flat lower ends 34. I also provide means to support the runner 28 in raised position on said pole 10, the preferred embodiment of said means 15 comprising the pin 50 adapted to be thrust through the hole 52 in said pole 10 to support said frame in raised position. Though I have shown the frame and pegs constructed of wood, it is obvious that they may be 20 constructed of aluminum or other preferably light metal without departing from the spirit of my invention.

I provide the guy ropes 60 preferably attached to the outer ends 56 of said ribs 16 25 and to tent pegs 58 spaced at a greater radial distance from the tent pole 10 than the respective rib ends 56. In my preferred embodiment which preferably comprises four ribs, four arms, four guy ropes, and a four 30 sided tent, I thread the guy ropes 60 through the two eyes 20 on the respective rib ends 56 on the same side of the tent, and I secure the ends 62 of said guy ropes 60 to tent pegs 58 35 on the same side of the tent opposite their respective rib ends 56 and spaced at a greater radial distance from the pole 10 than the rib ends. Thus each guy rope 60 is threaded through the two adjacent eyes on the same side of the tent to support the tent between 40 the rib ends and secured to the ground at an angle to said rib ends forming an inclined supporting plane on each side of the tent. It is obvious that the guy ropes may be attached to the tent pole 10 at an angle thereto 45 in any suitable fashion.

I provide the tent canopy 70 which is adapted to be mounted on said tent frame. The corners 72 thereof are adapted to be secured to the ground as usual by the tent 50 pegs 59 and the side walls thereof are supported by said inclined guy ropes 60 as just explained and as shown in Fig. 1. In my preferred embodiment I provide the tent with the top 74 to fit over the ribs 16 and 55 the four sides 76 having the loops 78 on the lower corners thereof for attachment to the tent pegs.

To set up the tent, attach the telescoping 60 sections 10^a 10^b and 10^c of the pole 10 together, raise the runner, ribs and brace arms from their closed position shown in Fig. 3 to the open position shown in Fig. 2, insert the pin 50 in the hole 52 to support the runner in raised position, insert the guy ropes 60 through the eyes 20 and to the tent pegs

58 at an angle as just explained, and mount the tent canopy 70 thereon securing the corners 72 to the ground by means of looping the loops 78 over the tent pegs 59.

To take down the tent, undo the corner 70 tent pegs 59, take off the tent canopy 70, unfasten and take out the guy ropes 60, pull the pin 50 out of the hole 52, lower the runner element 28, the ribs 16 and brace arms 32 from the open position shown in Fig. 2 to 75 the closed position shown in Fig. 3, take the tent pole sections 10^a, 10^b, and 10^c apart when the whole tent may be readily packed in a very compact bundle.

As is apparent from the above construction when the frame is raised to open position, the inclined inner ends 18 of the ribs 16 80 abut the enlarged pole top 14 to limit the outward movement so that the frame will always be opened to the desired angle to permit rain, etc. to readily run off and the inclined upper ends of the brace arms 32 rest 85 flatly against the lower sides of the ribs 16 thereby more strongly supporting the ribs 16 than has been done hitherto. When the 90 runner, brace arms and ribs are lowered to closed position the flat lower ends of the brace arms abut the flat upper surface of the runner element 28 to retain the entire frame 95 in very compact relationship for packing purposes. It is obvious that I have provided a tent structure which when packed for shipping purposes comprises a very compact and light bundle about thirty-six inches long which may be readily carried by a 100 tramp or packed in an automobile trunk.

It is obvious that the inclined guy ropes 60 for the first time in any kind of tent structure actually support the walls of the tent.

It is understood that my invention is not 105 limited to the specific embodiment shown and that various deviations may be made therefrom without departing from the spirit and scope of the appended claims.

What I claim as new and desire to secure 110 as Letters Patent is:

1. A collapsible tent, comprising a frame, 115 comprising a centre pole adapted to be inserted in the ground composed of detachable sections, and having its top radially enlarged, ribs having inclined inner ends and eyes mounted on the outer ends thereof, 120 hinges joining the inclined inner ends of said ribs to the side of the enlarged pole top, a runner element having a flat upper side 125 slidable on said pole, brace arms having flat lower ends and inclined upper ends, hinges joining the inclined upper ends of said brace arms to the under side of said ribs, hinges joining the flat lower ends of said brace arms to the flat upper side of said runner and means to support said runner in raised position on said pole, guy ropes each threaded through adjacent rib eyes and having their ends secured to tent pegs on the same 130

side of the tent opposite their respective rib ends spaced at a greater radial distance from the pole than the open rib ends and a tent canopy mounted on said frame having the 5 corners thereof secured to the ground by tent pegs and the side walls thereof supported by said inclined guy ropes.

2. A quadrilateral collapsible tent comprising a frame, comprising a centre pole having its top radially enlarged, four ribs having inclined inner ends and eyes mounted on the outer ends thereof, hinges joining the inclined inner ends of said ribs to the side of the enlarged pole top, a runner element having a flat upper side slidable on said pole, four brace arms having flat lower ends and inclined upper ends, hinges joining the inclined upper ends of said brace arms to the under side of said ribs, hinges joining the 10 flat lower ends of said brace arms to the flat upper side of said runner and means to support said runner in raised position on said pole whereby when the runner, brace arms and ribs are raised to open position the inclined inner ends of the ribs may abut the enlarged pole top to limit their outward movement and the inclined upper ends of said brace arms may rest flatly against the lower sides of said ribs and when the runner, brace arms and ribs are lowered to closed 15 position the flat lower ends of the brace arms may abut the flat upper side of the runner element.

3. A frame for use in collapsible tents comprising a centre pole composed of detachable sections and having its top radially enlarged, ribs having inclined inner ends and eyes mounted on the outer ends, hinges joining the inclined inner ends of said ribs to the side of the enlarged pole top, a runner element having a flat upper side slidable on said pole, brace arms having flat lower ends and inclined upper ends adapted when 20

4. An umbrella type of tent comprising a centre pole, rigid ribs projecting radially downwardly from the upper end of said pole, guy ropes attached to the outer ends of said ribs and tent pegs spaced at a greater radial distance from the pole than their respective rib ends and a tent canopy resting 25 on said ribs having the corners thereof secured to the ground by tent pegs and the side walls thereof resting upon and supported by said inclined guy ropes.

5. An umbrella type of tent comprising a centre pole, rigid ribs projecting radially downwardly from the upper end of said pole having eyes mounted on the outer ends thereof, guy ropes each threaded through the adjacent rib eyes and having their ends secured to tent pegs on the same side of the tent opposite their respective rib ends and a tent canopy mounted on said ribs having the corners thereof secured to the ground by tent pegs and the side walls thereof supported by 30 said guy ropes.

in raised open position to extend at an angle 45 upwards and radially outwards from said runner element to said ribs, hinges joining the inclined upper ends of said brace arms to the under sides of said ribs, hinges joining the flat lower ends of said brace arms to the flat upper side of said runner and means to support said runner in raised position on said pole whereby when the runner, brace arms and ribs are raised to open position the inclined inner ends of the ribs may abut the enlarged pole top to limit their outward movement and the inclined upper ends of said brace arms may rest flatly against the lower sides of said ribs and when the runner, brace arms and ribs are lowered to closed 50 position the flat lower ends of the brace arms may abut the flat upper side of the runner element.

4. An umbrella type of tent comprising a centre pole, rigid ribs projecting radially downwardly from the upper end of said pole, guy ropes attached to the outer ends of said ribs and tent pegs spaced at a greater radial distance from the pole than their respective rib ends and a tent canopy resting 55 on said ribs having the corners thereof secured to the ground by tent pegs and the side walls thereof resting upon and supported by said inclined guy ropes.

5. An umbrella type of tent comprising a centre pole, rigid ribs projecting radially downwardly from the upper end of said pole having eyes mounted on the outer ends thereof, guy ropes each threaded through the adjacent rib eyes and having their ends secured to tent pegs on the same side of the tent opposite their respective rib ends and a tent canopy mounted on said ribs having the corners thereof secured to the ground by tent pegs and the side walls thereof supported by 60 said guy ropes.

In testimony whereof I affix my signature.
ALICE F. LEACH.
